REMOVAL OF SULFUR

Filed Dec. 29, 1945

Hydrocarbons, such as gasoline, kerosene, fuel oil, etc., contain sulfur compounds which are objectionable because of their bad odor, their corrosive action on metal parts with which they come in contact, and particularly in gasolines, for their influence on color and haze formation and their adverse effect on the susceptibility to fuel additives such as lead tetraethyl and oxidation inhibitors. In conversions of hydrocarbon compounds the presence of sulfur compounds is frequently detrimental to the best results, especially in the poisoning and loss of catalyst, if it be used, and in the quality of the product where the sulfur originally present in the feed is often concentrated, such as in polymerization and alkylation processes in which light hydrocarbons are converted into motor fuels and the sulfur compounds are condensed into sulfur compounds of similar boiling range.

UNITED STATES PATENT OFFICE

2,478,603

REMOVAL OF SULFUR

Charles A. Stratton, Borger, Tex., assignor to
Phillips Petroleum Company, a corporation of
Delaware

Application December 29, 1945, Serial No. 638,402

5 Claims. (Cl. 196—33)

1

This invention relates to the treatment of hydrocarbons for the removal of sulfur compounds. More particularly, the invention relates to the removal of sulfur compounds from lighter hydrocarbons and the suppression of such compounds in motor fuels.

The removal of sulfur compounds or the conversion of these compounds into more innocuous compounds has always been a serious problem in the refining of hydrocarbon materials in which they were present. These sulfur compounds are generally present in the form of free sulfur, hydrogen sulfide, mercaptans, thiophenes and other sulfides. Their presence is objectionable for the bad odor, corrosion of metal parts with which they come in contact and, particularly in gasolines, for their influence on color and haze formation and their adverse effect on the susceptibility to fuel additives such as lead tetraethyl and oxidation inhibitors. In conversions of hydrocarbon compounds the presence of sulfur compounds is frequently detrimental to the best results, especially in the poisoning and loss of catalyst, if it be used, and in the quality of the product where the sulfur originally present in the feed is often concentrated, such as in polymerization and alkylation processes in which light hydrocarbons are converted into motor fuels and the sulfur compounds are condensed into sulfur compounds of similar boiling range.

While sulfur compounds in hydrocarbon products, such as gasolines, may be rendered substantially innocuous by various refining treatments such as sweetening processes, removal by absorption or adsorption, etc., it is preferable to remove the sulfur constituents from the original materials before subjecting the material to extensive refining or conversion processes in which the materials are involved.

It is therefore an object of this invention to provide a process for the substantial removal of sulfur compounds from hydrocarbons in which they are present.

Another object of the invention is to remove sulfur compounds from light hydrocarbons in a novel combination of washing treatments.

A further object is to provide for the removal of sulfur compounds from hydrocarbon mixtures by a series of interrelated alkaline and plumbite treating operations.

Other objects will be apparent from the specification and drawing in which the single figure is a schematic drawing of one embodiment of the invention.

According to the present invention, a stream of hydrocarbons is consecutively contacted with a series of alkaline washes of progressively increasing strength, at least the final wash of which contains plumbite in solution. It is known that alkaline solutions are useful in reacting with and removing sulfur compounds and it has now been found expedient and economical to include plumbite in the final washing stage and to advance the washing solutions through the several stages until the alkaline solution and/or plumbite is exhausted at which time the solutions may be regenerated. By the practice of the present method of treating and system of handling wash solutions, the effectiveness of the desulfurization is substantially increased.

A better understanding of the invention may be had by reference to the drawing which illustrates an embodiment of the process in which a hydrocarbon mixture is introduced by line 10 into a prewasher 11 in which the hydrogen sulfide is substantially removed by a solution of caustic. After contact with the caustic solution the hydrocarbon is allowed to separate from the caustic solution which is removed with product soluble sulfur salts through line 12. Until depleted below a suitable caustic concentration, the mixture may be recycled to the inlet stream by line 13. After depletion, the spent caustic solution may be withdrawn and fresh solution introduced. The treated hydrocarbon mixture is withdrawn via line 14 to a caustic washer 15 in which it is thoroughly contacted with an alkaline solution which is recycled from the same washer by line 16. After satisfactory contact, the hydrocarbon mixture is again separated and passed by line 17 to a second caustic washer 18 where it is again contacted with caustic solution from recycle line 19. Separation by stratification is again effected and the hydrocarbon is passed through line 20 to a third washer 21 and contacted with recycle caustic introduced into the stream via line 22. After treatment and separation therein the hydrocarbon is conducted by line 23 to a fourth washer 24 in which it is contacted with an alkaline plumbite solution from caustic

storage 25 through line 26. During contact in this last washer mercaptans are converted to lead mercaptides as well as soluble alkaline mercaptides. The lead mercaptides of the lighter mercaptans precipitate and are collected in the alkaline aqueous layer upon the separation of the hydrocarbon. The desulfurized hydrocarbon is removed after separation and passed to further treatment and storage, as desired, by line 27. Solid lead mercaptide is collected in the lower portion of the washer 24 until it is desirable to augment the concentration of plumbite in the caustic solution or until a sufficient amount of precipitated mercaptide has accumulated for regeneration in regenerator 28 into which the mercaptide is introduced through a funnel-shaped passage 29 which is opened and closed by a valve 30. Both expended caustic and plumbite may be regenerated simultaneously in the regeneration section as hereinafter described. The caustic solution containing unreacted plumbite and after being substantially separated from precipitated lead mercaptides may be recycled and admixed with the hydrocarbons through line 31. As the concentration of plumbite becomes somewhat reduced by reason of the removal of the lead through reaction to form insoluble lead mercaptide salts, the caustic solution may be transferred by line 32 to caustic washer 21 whose caustic solution may at the same time be removed or transferred by line 33 to the circulating system supplying the second caustic washer 18. Similarly the caustic solution of washer 18 is transferred to the first washer 15 through line 34 and the substantially exhausted caustic solution from washer 15 containing the soluble sulfur compounds is removed by line 35 or passed to the regenerator via line 36. Thus the caustic concentration in each consecutive washer is progressively higher for having been used a shorter length of time, the first washer 15 containing the lowest concentration. Air may be introduced into the regenerator through line 37 and spider distributor 38 and the regeneration may be accelerated by heating the solution being regenerated. Heat may be supplied through a heating coil 39 supplied with steam through line 40. Satisfactory regenerating temperatures may be about 210° F. and preferably between 100-400° F. Entrained hydrocarbons and some disulfides which form during regeneration are withdrawn as gases through line 41 while the major portion of the disulfides collects as an upper layer over the caustic solution in the regenerator and is removed by line 42. Any entrained liquid materials may be removed from the overhead gas in trap 43. The regenerated caustic and plumbite are passed to storage through line 44 for recycle to washer 24. Additional water, litharge and caustic may be added as required by line 45.

The system may be run through a series of about twenty-five caustic changes without any attempt being made at regeneration of the caustic or lead, fresh lead and caustic solution being added to washer 24 at each change. The spent caustic in washer 15 may be dumped during this period, and the lead mercaptide allowed to build up in the bottom of washer 24. Then, the washer may be cleaned out by any suitable means such as by hand and the lead mercaptide retained for use in regenerating future batches of caustic. Subsequently, each spent batch of caustic in the first washer 15 may be regenerated by adding a portion of the stored lead mercaptide

to it and blowing it with air. The regenerated caustic and lead is sent to storage, whence it can be drawn for use in washer 24. When the stored lead mercaptide is used up, washer 24 may again be emptied of precipitated lead mercaptide and regeneration continued.

The removal of the sulfur compounds and the regeneration may be represented by a series of chemical reactions. In the removal of hydrogen sulfide and the mercaptans in the caustic treatment, soluble sodium salts are formed and are removed with the aqueous alkaline solution. These reactions may be represented by the following equations:

The reaction between mercaptans and litharge (PbO) or plumbite (Na_2PbO_2) which is formed when litharge is dissolved in caustic may be expressed as follows:

where R may be an alkyl group or hydrogen, in which latter case the sulfur compound is hydrogen sulfide.

In regeneration the alkaline sulfur compounds are oxidized to disulfides which are removed. The reactions occurring in the regeneration may be represented

The disulfide compounds are removed as described, leaving an aqueous solution of caustic and litharge which will again form plumbite solution suitable for recharging to the plumbite-caustic washer. Other reactions and products such as sulfates may be forming at the same time but the principal reactions are assumed to be as described. The invention is not intended, however, to be limited by any discussion of the assumed reaction and changes taking place.

By the practice of the present invention, hydrocarbon mixtures which contain sulfur compounds are more effectively freed of those contaminating constituents. It is found that by desulfurizing according to the present process more undesirable sulfur compounds are removed than by treating with either caustic or plumbite solution alone and that the final treatment with caustic-containing litharge reduces the sulfur content of hydrocarbon stocks to a point at which they may be satisfactorily utilized in particular conversions, such as alkylation and polymerization where exceptionally low sulfur content is desirable. Therefore improved final conversion products are possible without further treatment thereof.

As an example of the effectiveness of the invention an alkylation stock consisting mainly of C_4 hydrocarbons, with some C_3 and C_5 constituents, is liquefied and treated according to the present process. The untreated hydrocarbon mixture, containing 0.08 per cent mercaptan sulfur and 0.0015 per cent hydrogen sulfide sulfur, is treated in a prewasher with a 10 per cent solution of caustic soda. Substantially all of the hydrogen sulfide is converted to sodium sulfide which remains dissolved in the caustic solution. The hydrocarbon mixture is treated successively in the caustic washers, as described, and is contacted in the final washer with an approximately twenty-five per cent caustic soda solution which contains 7.86 pounds of litharge (PbO) per bar-

rel of caustic solution. At the beginning of the cycle with fresh caustic and plumbite solution, the liquefied light hydrocarbon mixture is recovered from the process with no hydrogen sulfide sulfur and only 0.001 per cent of mercaptan sulfur. At the point when the lead salt has been substantially consumed as precipitated lead mercaptide and the mercaptan sulfur content of the product has risen to about 0.0025 per cent of mercaptan sulfur, the solutions in each washer are transferred to the next in series before it, fresh plumbite-caustic solution is introduced in the final washer and the solution from the first washer is passed to the regenerator, mixed with the precipitated lead mercaptide and the mixture regenerated by heating and air blowing as described above. About 35 per cent of the caustic soda is spent in formation of sodium mercaptide and substantially all the lead content is consumed during the completion of the treating cycle. The mercaptan sulfur content of the product by this procedure averaged 0.0015 per cent which represents an improvement of 25 per cent over the product of a comparable treatment in which the litharge is omitted in the last washer.

If the hydrogen sulfide content of the original feed stock is negligible or for other reason a pretreatment of the stock is unnecessary, the pre-washer may be omitted from the process and the hydrocarbon mixture treated as described thereafter. Similarly, additional or fewer caustic washers may be employed in the successive series of treatment and different concentrations of caustic may be used satisfactorily. Compounds, such as higher alcohols, stearates, etc. which are commonly used to prevent emulsification and which are not harmful to the process or its product may be used to prevent emulsification and foaming of the hydrocarbons in the caustic solutions. Likewise, caustic potash may be used in place of caustic soda if desired but the latter is usually more satisfactory and economical. Other minor changes will be recognized by those familiar with the art and may be made without departing from the spirit of the invention as disclosed and claimed below.

I claim:

1. A process for the substantial desulfurization of a relatively light hydrocarbon mixture containing sulfur compounds which comprises successively contacting a stream of said mixture with at least two concentrated caustic solutions of progressively increasing alkalinity in separate contact zones, contacting said stream in a final contact zone with a caustic solution containing litharge without the addition of sulfur, separating the desulfurized hydrocarbon mixture and separating precipitated lead mercaptides in said final contact zone, simultaneously transferring caustic solutions from each zone and said final zone to next preceding zone in line of hydrocarbon flow upon the substantial depletion of litharge in final zone, and removing spent caustic from the first contact zone and said precipitated mercaptides from said final zone.

2. A process for the substantial desulfurization of a liquefied relatively light hydrocarbon mixture containing sulfur compounds which comprises successively contacting a stream of said mixture with at least two concentrated caustic solutions of progressively increasing alkalinity in separate contact zones, contacting said stream in a final contact zone with a caustic solution containing litharge without the addition of sulfur, separating the desulfurized hydrocarbon mixture

and separating precipitated lead mercaptides in said final contact zone, simultaneously transferring caustic solutions from each zone and said final zone to next preceding zone in line of hydrocarbon flow upon the substantial depletion of litharge in final zone, cycling spent caustic from the first contact zone to a regenerating zone, adding said precipitated lead mercaptides to spent caustic in said regenerating zone, and regenerating the resulting mixture by blowing the same with air.

3. A process for substantially desulfurizing normally gaseous hydrocarbons containing sulfur compounds which comprises liquefying said hydrocarbons, successively contacting a stream of said hydrocarbons with at least two concentrated caustic solutions of progressively increasing alkalinity in separate contact zones, contacting said stream in a final contact zone with a caustic solution containing litharge without the addition of sulfur, separating the desulfurized hydrocarbon mixture and recovering precipitated lead mercaptides in said final contact zone, simultaneously transferring caustic solutions from each zone and said final zone to next preceding zone upon the substantial depletion of litharge in final zone, cycling spent caustic from first contact zone to a regenerating zone, adding said precipitated lead mercaptides to spent caustic in said regenerating zone, and regenerating the resulting mixture by blowing the same with air.

4. A process for substantially desulfurizing a stream of gaseous hydrocarbons consisting substantially of butane which comprises liquefying said hydrocarbons, contacting said liquefied stream with a caustic solution in a prewasher to substantially remove hydrogen sulfide, successively contacting said stream with a concentrated caustic solution of progressively increasing alkalinity in at least three contact zones and with a plumbite solution comprising litharge dissolved in an approximate 25 per cent caustic solution in a final contact zone without the addition of sulfur, separating the desulfurized hydrocarbon and recovering precipitated mercaptides from the caustic solution in the final contact zone after depletion of litharge therein, simultaneously transferring the caustic solution in each contact zone and said final zone to the next preceding contact zone in line of flow of hydrocarbons and transferring the spent solution from the first contact zone to a regenerating zone, removing said precipitated mercaptides from final contact zone to said regenerating zone, simultaneously regenerating said spent caustic and plumbite solutions, and recycling the regenerated caustic litharge solution to the final contact zone.

5. A process for the substantial desulfurization of a relatively light hydrocarbon mixture containing sulfur compounds which comprises successively contacting a stream of said mixture with at least two concentrated caustic solutions of progressively increasing alkalinity in separate contact zones, contacting said stream in a final contact zone with a caustic solution containing litharge without the addition of sulfur, separating the desulfurized hydrocarbon mixture and separating precipitated lead mercaptides in said final contact zone, simultaneously transferring caustic solutions from each zone and said final zone to next preceding zone in line of hydrocarbon flow upon the substantial depletion of litharge in the final zone, cycling spent caustic from the first contact zone to a regenerating zone, adding said precipitated lead mercaptides to spent caustic in

said regenerating zone, and regenerating the caustic litiarge solution by blowing the same with air.
